HELMET FOR ACETYLENE WELDERS

Raleigh T. Shields, Newport News, Va.

Application July 12, 1943, Serial No. 494,380

3 Claims. (Cl. 2-8)

My invention relates to improvements in helmets such as are worn by acetylene welders, and of the type in which welding operations are viewed through a colored glass panel for protecting the eyes, and clear glass panels for protecting the colored panel.

The primary object of my invention is to equip such helmets inexpensively, and without complicating the structure, for removing the colored glass panel out of the range of vision, at will, and without using the hands, so that clear vision may be had through the clear glass panel, whenever desired, for instance, when attaching the electrode in the electrode holder.

Another object is to provide for protecting the eyes from flying hot metal, or flux, and also from the arcs of the other welders nearby.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in vertical section of a welder's helmet embodying my improvements.

Figure 2 is a view in rear elevation, drawn to an enlarged scale.

Figure 3 is a view in vertical section taken on the line 3-3 of Figure 2.

Figure 4 is a view in horizontal section taken on the line 4-4 of Figure 2.

Figure 5 is a fragmentary view in perspective of the third frame for the colored glass panel, and showing the manner in which the legs of the yoke are attached to said frame.

Figure 6 is a view in perspective of the yoke swinging member, drawn to an enlarged scale.

Figure 7 is a fragmentary view in front elevation of a modification of the invention, and

Figure 8 is a similar view in rear elevation of another modification of the invention.

Referring to the drawings by numerals, the helmet 1, shown fragmentarily, and having the rectangular sight opening 2 in the front thereof, is, according to my invention, equipped as follows:

A rectangular, flat plate 3 is bolted, as at 4, around its top and side edges to the inner face of the helmet 1, and which is constructed on its front side, and adjacent the bottom thereof, to form an internally channeled, relatively smaller, rectangular keeper frame 5 projecting forwardly through and fitted in the opening 2, said frame

containing a clear, rectangular glass panel 6. In the rear thereof, the plate 3 is constructed to form a second keeper frame 7 spaced laterally rearwardly from the frame 5 and opposite thereto, and which is similar to the frame 5. A second rectangular, rear, clear glass panel 8 is fitted in the second, or rear, frame 7. A rectangular panel 9 of dark colored glass and substantially the same size as the panels 6, 8, is mounted in the space between the frames 5, 7, in a third rectangular keeper frame 10 similar to the frames 5, 7, but provided with right angled end wear plates 11 suitably secured thereto. The third frame 10 normally rests on a bottom ledge 12 forming a part of the plate 3 and extending between the bottoms of the frames 5, 7, and is vertically movable out of the space between the frames 5, 7 into a rectangular hood 13 formed on the plate 3 above the frames 5, 7, and which is open at its sides and forms above the frames 5, 7 a guideway for the third frame 10. A pair of transversely right angled, vertically disposed keeper and reinforcing bars 14 fit along the sides of the plate 3, on the rear side of the latter, and overlap the rear side of the frame 7 at the ends of said frame, said bars closing the sides of the hood 13 and forming together with the ends of the frames 7 and 10 vertical ways 15 at the sides of the hood 13 and at the ends of said frames 5 and 7. The bars 14 are provided with bayonet slots 16 therein for hooking over the bolts 4 so that said bars are detachably attached to said plate 3 along the side edges thereof.

A U-shaped yoke 17 straddles the ends of the third frame 10 with its terminals pivoted, as at 18, to lugs 19 on the wear plates 11, the arrangement being such that the legs of the yoke are movable vertically in the ways 15 to move the third frame 10 upwardly, and said yoke depends below the plate 3 and is swingable laterally forwardly and rearwardly. Coil springs 20 suitably connected to the legs of the yoke 17, and to the plate 3, within the ways 15, tend to swing the yoke forwardly substantially parallel with the plate 3. The yoke 17 is provided with a stem 21 threaded into a socket 22 on the yoke to depend centrally from the yoke, and said stem terminates in a lower end ledge 23 extending inwardly toward the mouth of the wearer of the helmet and normally located below the mouth, as shown in Figure 1. The ledge 23, as will presently more clearly appear, forms a mouthpiece.

A right angled yoke swinging member 24 comprising an upstanding bar 25 and a right angled chin plate 26 is pivotally mounted adjacent the

juncture of said bar and plate on the front of the helmet 1 so that the arm 25 extends upwardly between said front and the stem 21, and the plate 26 underlies the chin of the wearer of the helmet, the arrangement being such that the plate 26 may be depressed by the chin to rock the member 24 and cause the bar 25, through engagement with the stem 21, to swing the yoke rearwardly toward the face of the wearer so that the ledge 23 may be entered into the open mouth of the wearer of the helmet.

The mounting for the member 24 comprises a clip 27, a pivot pin 28 extending through the clip and through a hinge barrel 29 on the bar 25, a thumb screw 30 threaded through the front of the mask and having the clip swiveled on the inner end thereof, and a jam nut 31 on said screw. The thumb screw 30 and nut 31 provide for properly adjusting the member 24 on the helmet toward and from the face of the wearer of the helmet.

In the modification of the invention shown in Figure 7, the front frame, designated 32 in this instance, is provided with a suitable end piece 33 pivoted, as at 34, for swinging movement to open one end of the frame so that the glass panel 35 may be replaced if broken.

In the modification shown in Figure 8, the rear frame, designated 36, is provided with a removable end 37 secured to the top and bottom of the frame by spring fingers 38 engaging apertured lugs 39. A finger grip 40 is provided on the end 37 to facilitate removing the same. By removing the end 37, the frame 36 may be opened for replacement of the rear glass panel 41, should occasion require.

The operation of the described invention will be readily understood. For clear vision through the sight opening 2 and the clear glass panels 6 and 8, the wearer of the mask opens his, or her, mouth thereby, through lowering of the chin, operating the member 26 to swing the yoke 17 and enter the ledge 23 in the mouth to be lifted by closing of the lower jaw. This operation lifts the yoke 17 and the third frame 40 so as to move the colored glass panel 9 upwardly clear of the opening 2. The operator may hold the ledge 23, or mouthpiece, between the teeth to hold the colored glass panel 9 raised as long as desired. As soon as the ledge 23 is released, the springs 20 retract the yoke 17 and the yoke and the third frame 40 drop to normal position. A suitable spring 42 is connected to the arm 25 of the member 24 to return the member to normal position as soon as the member is released by closing of the lower jaw.

The foregoing will, it is believed, suffice to impart a clear understanding of my invention without further explanation.

Manifestly, the invention is susceptible of modification without departing from the inventive concept, and right is herein reserved to such modifications as fall within the scope of the appended claims.

What I claim is:

1. In a helmet to be worn by welders and having a sight aperture in the front thereof, a colored glass panel for protecting the eyes of the wearer, means to mount said panel in said helmet for movement in opposite directions into and from covering relation to said aperture, means to move said panel in one direction comprising a mouthpiece swingably mounted for movement toward and from the mouth of the wearer, and means operative by opening movement of the lower jaw of the wearer to move said mouthpiece toward the mouth.

2. In a helmet to be worn by welders and having a sight aperture in the front thereof, a colored glass panel for protecting the eyes of the wearer, means to mount said panel in said helmet for movement in opposite directions into and from covering relation to said aperture, means to move said panel in one direction comprising a mouthpiece swingably mounted for movement toward and from the mouth of the wearer, and means operative by opening movement of the lower jaw of the wearer to move said mouthpiece toward the mouth, the first-mentioned means comprising a yoke pivotally mounted on said panel, and a ledge on said yoke for entering the mouth.

3. In a helmet to be worn by welders and having a sight aperture in the front thereof, a colored glass panel for protecting the eyes of the wearer, means to mount said panel in said helmet for movement in opposite directions into and from covering relation to said aperture, means to move said panel in one direction comprising a mouthpiece swingably mounted for movement toward and from the mouth of the wearer, and means operative by opening movement of the lower jaw of the wearer to move said mouthpiece toward the mouth, the first-mentioned means comprising a yoke pivotally mounted on said panel and depending therefrom, the second-mentioned means comprising a rocking member underlying the lower jaw of the wearer and operatively related to the yoke to swing the same toward the mouth.

RALEIGH T. SHIELDS.
